DESIGN FOR A TELEPHONE JACK BRACKET

Leslie B. Haigh, West Orange, and Franklin A. Stearn, Westfield, N. J., assignors to Federal Telephone and Radio Corporation, New York, N. Y., a corporation of Delaware

Application March 17, 1945, Serial No. 118,529

Term of patent 14 years

(Cl. D26—13)

To all whom it may concern:

Be it known that we, Leslie B. Haigh and Franklin A. Stearn, a subject of Great Britain and a citizen of the United States, and residents of West Orange and Westfield, in the counties of Essex and Union, respectively, and both State of New Jersey, United States of America, have invented a new, original, and ornamental Design for Telephone Jack Bracket, of which the follow-

ing is a specification, reference being had to the accompanying drawing, forming part thereof.

The figure is a perspective view of the telephone jack bracket, showing our new design.

We claim:

The ornamental design for a telephone jack bracket, as shown.

LESLIE B. HAIGH.
FRANKLIN A. STEARN.
